US00D848271S

(12) **United States Design Patent** (10) Patent No.: **US D848,271 S**
Galvin et al. (45) Date of Patent: **** May 14, 2019**

(54) **BOTTLE**(71) Applicant: **PepsiCo, Inc.**, Purchase, NY (US)(72) Inventors: **Ian Galvin**, Chicago, IL (US);
Raymundo Martinez, Berwyn, IL (US);
Katie Ozamiz, Seattle, WA (US);
Wade Fournier, Chicago, IL (US)(73) Assignee: **PepsiCo, Inc.**, Purchase, NY (US)(***) Term: **15 Years**(21) Appl. No.: **29/627,107**(22) Filed: **Nov. 22, 2017**

Primary Examiner — Karen S Acker

Assistant Examiner — Omeed Agilee

(74) Attorney, Agent, or Firm — Sterne, Kessler, Goldstein & Fox P.L.L.C.

(57) **CLAIM**

The ornamental design for a bottle, as shown and described.

DESCRIPTION

FIG. 1 is a top front perspective view of a bottle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 7 Drawing Sheets

See application file for complete search history.
